UNITED STATES PATENT OFFICE.

RICHARD E. SCHWARZ, OF ROYAL OAK TOWNSHIP, OAKLAND COUNTY, MICHIGAN.

SHINGLE-MACHINE.

1,396,468.

Specification of Letters Patent. Patented Nov. 8, 1921.

Application filed March 5, 1921. Serial No. 449,832.

To all whom it may concern:

Be it known that I, RICHARD E. SCHWARZ, a citizen of the United States, and residing at Royal Oak township, in the county of 5 Oakland and State of Michigan, have invented a new and Improved Shingle-Machine, of which the following is a specification.

This invention relates to machines for continuously making shingles from semi-fluid mixtures of cement and other mineral substances, and its object is to provide an automatically operating machine which will produce shingles which may be either of even 10 thickness or have any desired taper, as desired, which machine shall be simple in construction, of great strength and of great capacity.

This invention consists in an intermittently operating conveyer for molds, a device for delivering a predetermined amount of material to each mold as it is presented to this supply device, and of means for removing the excess water from the material 20 in the charged mold as the mold is presented to this water-removing device.

It further consists in a conveyer in the form of a pair of chains provided with supporting wheels, a track for the wheels, and 30 a support for the molds below the water-removing device, the tracks at this point being provided with depressions to permit the molds to rest on the support.

It also consists in a water-removing device comprising a stationary piston, a cylindrical pressure box slidable thereon and having an internally extending flange along 35 its lower edge of the same outline as the mold, and means to supply compressed air to the space below the piston to coat with said flange and hold the flange against the mold.

It also consists in a mold with rubber covered sides adapted to engage the flange on the pressure box of the water-removing device so as to provide an air tight joint.

It also consists in a spring to normally support the pressure box of the water-removing device and in means operated at each cycle of the machine to force down the 50 pressure box so that the flange at its lower edge may engage the mold thereunder.

It also consists in the details of construction illustrated in the accompanying drawings and particularly pointed out in the 55 claims.

In the accompanying drawings, Figure 1

is a side elevation of this improved shingle machine. Fig. 2 is a section on the line 2-2 of Fig. 1. Fig. 3 is a vertical section of a pressure box and its guiding mechanism. 60 Fig. 4 is a section on the line 4-4 of Fig. 3 on a smaller scale. Fig. 5 is a section on the line 5-5 of Fig. 4 on a larger scale showing the mold in position. Fig. 6 is a detail section of a mold on the line 6-6 of Fig. 11. 65 Fig. 7 is a vertical section of a mold filler. Fig. 8 is a section on the line 8-8 of Fig. 7. Fig. 9 is a detail showing the control mechanism. Fig. 10 is a detail showing the valve operating mechanism of the mold filler. 70 Fig. 11 is a plan of a mold. Fig. 12 is a detail of the mold carrier. Fig. 13 is a dia-grammatic detail of the driving mechanism. Fig. 14 is a section of an air valve. Fig. 15 is a detail of a valve lever. 75

Similar reference characters refer to like parts throughout the several views.

In the present machine an endless double chain carries shallow molds having foraminous bottoms to a filling device and stops. 80 A predetermined amount of semi-fluid mixture containing cement and other materials adapted to produce shingles is dropped into the mold. The chain then carries the mold to the device for expressing the excess water, 85 lowers the mold onto a support and stops. A pressure box now comes down onto the mold and seals the edges thereof and air pressure in the space above the mold causes all excess of water to be expressed from the 90 plastic mass.

The pressure box is now lifted and the chain lifts the mold from its support and carries it to the point of discharge. Because of the many advantages, the present 95 machine is built in duplicate, although one half may be omitted if desired.

The molds.

The shingle molds used in the present machine (Fig. 11) are rectangular with sides 1, ends 2 and partitions 3, so that two shingles may be made in one mold. The sides and ends are preferably formed by covering a pipe 4 (Fig. 5) with a layer of rubber 105 5 so as to provide a flat upper side 6. A continuous outside frame member 7 supports an angle bar 8 at each side, as indicated in Fig. 5. The partitions 3 are shown in Fig. 6 to consist of central tubes 9 of metal with a coating 10 of rubber, the central tubes connecting at their ends to the 110

pipes. The bottom of each mold is made up of a strong metal plate 11 having comparatively large perforations and a thin sheet 12 with very small and closely spaced 5 perforations or a finely woven wire screen resting on the plate 11. The plate 11 is there to support the screen 12. If desired, the parts 7 and 11 may be made integral.

10   *The driving mechanism.*

In Fig. 1 the chain wheels are shown to have six teeth and the molds are carried by alternate links of the conveyer chain. It is therefore necessary to advance the 15 chains a distance equal to the length of two links for each cycle of the machine. The driving mechanism for the shaft 14 of the head wheels 15 may be mounted directly upon or be spaced somewhat from the frame 20 of the machine and may consist of a shaft 14^a adapted to be connected to the shaft 14 or be a part thereof, a pinion 16 on this shaft 14^a, a gear 17 meshing therewith and mounted on the shaft 18, a Geneva-movement star wheel 19 on this shaft 18, a disk 20 on the main driving shaft 22, said disk carrying the usual pin 23 and a mutilated plate 24 employed in Geneva-movements. The shaft 22 makes one revolution for each 30 cycle of the machine and may be driven in any desired manner, a belt 25 being indicated. A sprocket chain 26 on the sprocket wheel 27 on this main shaft 22 connects to the sprocket wheel 28 on the control shaft 35 29 shown in Fig. 1 and these wheels are of equal size so that the shaft 29 makes one revolution for each cycle of the machine. The pinion 16 and gear 17 are as 3 to 5, so that the shaft 14 will make one- 40 third revolution for each cycle of the machine. It will be understood that any other desired mechanism may be employed to drive this shingle mechanism and to control its operations.

45   *The frame and carrier chain.*

As the present machine is substantially automatic in its operation, it may be constructed in duplicate to great advantage. 50 The frame is shown to consist of the horizontal bars 32, 33 and 34, the upright bars 35, 36, 37, 38 and 39, and cross bars 40 and 41, but this is merely a convenient construction and may be varied by any skilled designer. In order to form tapering shingles when these are desired, the plastic mass must be thicker at one end of the mold than at the other. This is provided for by the arc-shaped shoes 42 under one end 55 of the frame and the screws 43 under the opposite end of the frame. I prefer to have these shoes 42 central with the shaft 14 so that the driving shaft of the machine will always remain in alinement with the head 60 shaft of the conveyer. The shoes may rest

on rollers 44 supported in any desired manner.

The shaft 45 of the rear chain wheels 46 may be mounted in any well known type of adjustable bearing 47. The chains are each 70 formed of flat side links 48 and 48^a in pairs connected by short pins 49 which alternate with transverse rods 50 which extend across between the two chains. Flanged carrier wheels 52 are mounted on the pins 49 and 75 rods 50, and these wheels ride on the tracks 53 and 54.

To each alternate inner link 48 of each chain is attached an angle bar 55 of such a length that it extends forward sufficiently to 80 overlap substantially one half of the length of the adjacent link 48^a, see Fig. 12. The molds are mounted on these angle bars in the manner shown in Fig. 2. The upper tracks are formed with pairs of depressions 85 at 56 and 57, as indicated in Fig. 1.

85   *The mold filler.*

The shingle material is in the form of a more or less liquid mass stored in a tank 90 above the carrier and extending down therefrom is a measuring device shown in cross section in Fig. 7. It is built up of a series of cylindrical members, among them being the telescoping parts 61 and 62 which 95 permit of the tank 60 and the tube 61 being raised or lowered to vary the capacity of the measuring device. Two valve seats 63 and 64 are mounted within the measuring device and valves 65 and 66 are mounted 100 on the stem 67 and are adapted to alternately engage these seats. A link 68 at the lower end of the stem 67 connects to a pin 91 at the end of a second link 69^a pivoted at 70. The pin 91 extends through a slot 71 in a 105 lever 69 as indicated in Fig. 15. Because of this slot, the spring 88 may hold the link 68 and stem 67 at their high or low positions, irrespective of any looseness of the connections between the pivot 70 of the 110 lever 69 and the end of the lever 86 that engages the cam 81. It will be noticed that this spring 88 swings across the pivot 70 to hold this pin 91 at the end of its up or down movements.

Fig. 1 shows a pair of channel beams 73 resting on the bars 33 and Fig. 2 shows posts 74 extending upward from these channel beams and supporting other channel beams 75. The posts carry sleeves 76 which are 120 adjustable by means of nuts 77. Brackets 78 on these upper channels support the bearings 79 for the control shaft 29 above referred to, and on this shaft are mounted three cams 81, 82 and 83, which are shown 125 in Fig. 9 in the positions they occupy at about the middle of the rest period of the conveyer.

On a bracket 78 is a pedestal 84 which carries a pivot 85 for the lever 86, the forward 130

end of which engages the cam 81, and the rear end connects to the link 87 which extends to the lever 69.

When the valve 66 is raised, the material 5 in the tubes 61—62 will flow down through the holes 92 and divide, one-half passing down each leg 93 into a mold carried by each conveyer, and the elevation of the valve 66 will also cause the valve 65 to close the 10 openings 94 in the valve seat 63 until the measuring device has been discharged. The legs 93 are attached to the angle bar 95 by means of clamps 96 and this angle bar is secured to the posts 38. The tube 61 may be 15 provided with an air vent 61^a.

The water removing device.

When the mold has been filled it is carried along a short distance and laid upon a support 97, substantially rectangular in plan, 20 and having an outside wall 98 and cross bars 99. The bottom plate 11 of the mold rests directly on these walls and cross bars and these supports are carried by the channel 25 bars 73. Mounted in the channel bars 75 and positioned by the pins 100 are the internally threaded blocks 102 into which the piston rods 103 are screwed. On these piston rods are the stop nuts 104 and the piston 30 tons 105.

Slidable on the piston rods are the pressure boxes 106 whose conical tops 107 are formed with hubs 108, to which the channel beams 109 are attached by means of the pins 35 111 and sleeves 111^a of a universal coupling. A pin 110 connects the middle points of these channel beams to the head 112 of the piston rod 113. A cylinder 115 is shown in Fig. 2 to have a piston 114, shown in dotted 40 lines, attached to the lower end of the piston rod 113. Within the pressure boxes and on the piston rods 103 and resting on the pistons 105 are springs 116 which normally hold up the mold covers.

45 The cam 82 on the shaft 29 actuates a lever 117 mounted on a pin 118 carried by a block 119 on the bracket 78. As soon as the conveyer chains have brought a pair of filled molds to the supports 97 and lowered the 50 molds down onto the supports by the wheels 52 descending into the depressions 56 and 57 in the rails 54, the cam 82 swings the lever 117 against the pull of the spring 120 and opens the valve between the air main 55 122 and the pipe 123 leading to the cylinder 115, admitting compressed air to this cylinder above the piston 114 and forcing down the piston and the two pressure boxes 106. The lower ends of the pressure boxes are 60 formed with inwardly extending flanges 124 (Fig. 5), which fit against the surfaces 6 of the rubber rims of the molds.

A valve adapted to control the cylinder 115 is shown in Fig. 14 and comprises a body 65 125 in which a disk valve 126 is held against

its seat by the spring 127 and pressure from the pipe 128 leading to the main 122. A stem 129 on this disk valve may be depressed by the member 130 connected to the arm 131 which in turn is operatively connected to the lever 117 by a link 132. When the arm 131 is swung to the position shown in Fig. 14, the air in the pipe 123 may escape through the opening 133.

As soon as the pressure boxes have been 75 brought down onto the molds as just described, the cam 83 swings the lever 134 against the pull of the spring 135 to swing the valve lever 136 of the valve 137, which levers are connected by the link 138. Air 80 from the main 122 passes down the pipe 139 to the T 140 and through the pipes 141 to the pistons 105, see Fig. 5. The pistons are formed with irregular annular passages 142 and 143 and the annular outlet is so large 85 that there is no blast of air directed against the material in the mold to disturb it.

Each piston may be formed with a packing ring 145, and its diameter is so much greater than the flange 124 of the pressure 90 box that the pressure of the air below the piston will hold the pressure box down on the mold. The pressure of the air below the piston forces all excess water down through the screen 12 into the support 97 95 from which it may escape through the opening 144.

Very little time is necessary to drive off the excess water and the pressure boxes are permitted to rise under the push of the 100 springs 116. The conveyer then carries the mold forward and discharges it onto the incline 147 as indicated in Fig. 1, from which it is removed to the seasoning floor.

While I have shown a mold for rectangular shingles and more rectangular molds will probably be used than any other type, it will be understood that the mold may be given any desired interior form so as to produce shingles of any design. 105 110

I prefer the present construction with its use of air pressure above the mold to the use of a suction pump attached to the mold support at the discharge openings 144 thereof, for while the joint between the molds and the support can easily be made air tight, the absolute pressure above the mold can only equal fifteen pounds per square inch when suction is employed, whereas by the present system any desired pressure may be had, 115 120 about eighty pounds being found the most desirable.

The details of construction and the proportions of the parts may all be changed by those skilled in the art without departing 125 from the spirit of my invention as set forth in the following claims.

I claim:—

1. In a shingle machine, the combination 130 of a conveyer chain adapted to carry shingle

- molds, said chain embodying carrier wheels, a track for said wheels, a support to hold the molds while the excess water is forced therefrom, and rails on which the carrier wheels 5 may travel, said rails having depressions so that the chains may lower the molds onto the support.
2. In a shingle machine, the combination with rectangular molds having the upper 10 edges of their rims flat, a conveyer for the molds, a support for the molds, a mold cover comprising a vertically movable body whose lower end conforms to the rim of the mold and having inwardly extending flanges at 15 said lower end, and means to introduce air under pressure above the material in the mold.
3. In a shingle machine, the combination of a series of molds, a conveyer for said 20 molds embodying a pair of chains, chain wheels on which the chains are mounted, means to intermittently actuate the chain, means to discharge a predetermined amount of shingle material at each rest of the conveyer, and means to produce a pressure of air 25 above a mold at each rest of the conveyer.
4. In a shingle machine, the combination of a frame, a series of molds, a conveyer 30 adapted to receive said molds, a track for the conveyer mounted on the frame, and means to incline the frame to cause the material in the molds to be deeper at one end than at the other.
5. In a shingle machine, a mold comprising 35 an exterior frame of metal and a rubber covering therefor having a flat top, a bottom for the mold comprising a relatively heavy bottom plate provided with perforations and a finer screen thereon, a mold cover having 40 a flat bottom adapted to engage the rubber covering of the mold frame, and means to convey air under pressure to the space above the mold.
6. In a shingle machine, a rectangular 45 mold comprising an exterior frame of metal and a rubber covering therefor having a flat top, a screen for the bottom of the mold adapted to permit the passage of water, a support for the mold, a piston rigidly 50 mounted above the support, a mold cover embodying a cylindrical portion slidable on the piston and a rectangular lower end adapted to fit the mold, the cylindrical portion having greater area than the clear space 55 within the rectangular end, and means to move the cover up and down.
7. In a shingle machine, a rectangular mold comprising an exterior frame of metal and a rubber covering therefor having a flat 60 top, a screen for the bottom of the mold adapted to permit the passage of water, a support for the mold, a piston rigidly mounted above the support, a mold cover embodying a cylindrical portion slidable on 65 the piston and a rectangular lower end
- adapted to fit the mold, the cylindrical portion having greater area than the clear space within the rectangular end, a spring to lift the cover from the mold, and a cylinder and piston to force the cover down onto the 70 mold.
8. In a shingle machine, a rectangular mold comprising an exterior frame of metal and a rubber covering therefor having a flat 75 top, a screen for the bottom of the mold adapted to permit the passage of water, a support for the mold, a piston rigidly mounted above the support, a mold cover embodying a cylindrical portion slidable on the piston and a rectangular lower end 80 adapted to fit the mold, the cylindrical portion having greater area than the clear space within the rectangular end, means to move the cover up and down, and an intermittently movable conveyer for carrying the 85 molds to said support and then removing them.
9. In a shingle machine, a rectangular mold comprising an exterior frame of metal and a rubber covering therefor having a flat 90 top, a screen for the bottom of the mold adapted to permit the passage of water, a support for the mold, a piston rigidly mounted above the support, a mold cover embodying a cylindrical portion slidable on 95 the piston and a rectangular lower end adapted to fit the mold, the cylindrical portion having greater area than the clear space within the rectangular end, means to move the cover up and down, and a frame on which the support is mounted, and means to incline the frame, support and mold.
10. In a shingle machine, a pressure box, a mold support below the pressure box, a mold conveyer comprising a pair of chains, 105 one on each side of the pressure box and adapted to place molds on the pressure box, and means to lower the pressure box onto the molds.
11. In a shingle machine, a pressure box, 110 a mold support below the pressure box, a mold conveyer comprising a pair of chains and a carrier wheel at each link of said chains, tracks for the wheels formed with depressions adjacent the mold support to 115 lower the chains and the molds thereon so that the molds may rest on the support, and means to lower the pressure box onto the molds.
12. In a shingle machine, a pressure box, 120 a mold support below the pressure box, a mold conveyer comprising a pair of chains and a carrier wheel at each link of said chains, tracks for the wheels formed with depressions adjacent the mold support to 125 lower the chains and the molds thereon so that the molds may rest on the support, means to lower the pressure box onto the molds.
13. In a shingle machine, a head shaft, 130

- two pairs of chain wheels mounted thereon, conveyer chains in pairs on said wheels, mold supports attached to the inner sides of said chains, a tubular measuring device for semi-
5 liquid shingle material, tubular legs attached thereto to discharge the contents thereof into molds between the pairs of chains, and means for intermittently operating the measuring device and the chains.
- 10 14. In a shingle machine, a head shaft, two pairs of chain wheels mounted thereon, conveyer chains in pairs on said wheels, mold supports attached to the inner sides of said chains, a tubular measuring device for semi-
15 liquid shingle material, tubular legs attached thereto to discharge the contents thereof into molds between the pairs of chains, means for intermittently operating the measuring device and the chains, and means above each conveyer to cause the removal of the excess 20 water in the shingle material in the molds carried by the conveyer.

RICHARD E. SCHWARZ.
